UNITED STATES PATENT OFFICE.

ALBERT R. CLARKE, OF SHERIDAN, WYOMING, ASSIGNOR, BY DIRECT AND MESNE ASSIGNMENTS, TO CLARKE ELECTRIC HEATER COMPANY, A CORPORATION OF WYOMING.

RADIATOR-HEATER.

1,227,529.

Specification of Letters Patent. Patented May 22, 1917.

Application filed February 21, 1916. Serial No. 79,761.

To all whom it may concern:

Be it known that I, ALBERT R. CLARKE, a citizen of the United States, residing at Sheridan, in the county of Sheridan, State 5 of Wyoming, have invented certain new and useful Improvements in Radiator-Heaters; and I do hereby declare the following to be a full, clear, and exact description of the invention, such as will enable others skilled 10 in the art to which it appertains to make and use the same.

This invention relates generally to combustion engines, and particularly to the cooling systems thereof.

15 The invention may be more particularly identified with combustion engines employing water cooling systems, and aims primarily to provide a simple and efficient means for maintaining the water in the cooling system at a degree of temperature above the freezing point, particularly when the engine is at a standstill.

20 The invention aims further to provide means capable of ready application to the water cooling system of a motor or combustion engine such as is commonly used in motor vehicles, which may derive its heat from the batteries or other electrical source usually employed with such motors, and which 25 is of such construction or arrangement as to require but low voltage and amperage for its perfect operation.

A still further object of the invention is to provide a device of the character described 35 which is composed of comparatively few inexpensive and readily assembled parts, each of which is so arranged when the device is assembled as to preclude the possibility of breakage or derangement of the same, which, 40 as a whole, may be quickly and easily attached or detached from a water cooling system of a motor, and which will prove thoroughly efficient in the attainment of the ends for which it is designed.

45 With these objects in view, together with others which will appear as the description proceeds, the invention resides in the novel combination and arrangement of parts all as will be described more fully hereinafter, 50 illustrated in the drawings and particularly pointed out in the claims.

The invention will be best understood by reference to the accompanying drawings, wherein:

Figure 1, is a side elevation of a conventional form of engine of the internal combustion type with the usual water cooling system attached thereto, and illustrating the application of a heater constructed in accordance with my invention, 55

Fig. 2, is an enlarged vertical sectional view taken through the improved heater,

Fig. 3, is a top plan view of the improved heater, and

Fig. 4, is a diagrammatic view illustrating 65 the manner in which the heater is connected with the batteries of the motor.

Referring now more particularly to the drawings 5 indicates a conventional form of motor or gas engine, and 6 a radiator of 70 the ordinary construction, the latter being connected with the water jackets of the engine cylinders by a pipe 7 at one end, and by a pipe 8 at its lower end. As is well known to those familiar with motors of this type, 75 a pump 9 is used, and a flexible tubing or hose 10 is usually arranged to connect the pump inlet with the pipe 8 projecting rearwardly from the lowermost portion of the radiator. It is within this flexible tubing or 80 hose 10 that I preferably install my water heating device.

In carrying out the invention, I employ a tubular member 11, made of any suitable light material such as aluminum, and arranged to provide an enlarged portion 12 intermediate its ends, from which an outwardly projecting interiorly threaded nipple 13 projects. The tubular member thus formed presents substantially a T-joint, to 90 the outwardly projecting ends of which are connected the ends of the flexible tubing or hose connecting the pipe 8 with the pump inlet.

An exteriorly threaded bushing 14 is arranged for insertion in the nipple 13, and cemented or in any other suitable manner secured to depend from the lowermost edges of the bushing is a relatively thin porcelain shell 14', said shell having its free end 100 closed, and having its opposite end seated against a shoulder formed in the inner sur-

face of the bushing, so that it constitutes a substantial continuation of said inner surface. This shell is substantially equal in diameter to that of the bushing, and projects 5 within the enlarged portion 12 of the tubular member to be contacted by water passing therethrough. A gasket 15, preferably of copper, is inserted between the shoulders of the nipple and the bushing to prevent 10 leakage at the seat of the water, and this gasket is provided with an outwardly projecting arm or portion 16, upon which a binding screw 17 is arranged. A core 18, formed of porcelain, is adapted for insertion 15 within the shell 14', the said core being of such dimension as to provide a space between the innermost end and side walls of the same and the interior walls of the porcelain shell 14'. This core may be provided at its outer 20 most end with a screw member 19, exteriorly threaded as shown for engagement with the threads upon the interior surface of the bushing 14. The core 18 is preferably cemented to the said screw member, and is pro- 25 vided with a centrally disposed bore through which a wire 20 extends, the said wire protruding beyond the lowermost end of the core and for the remainder of its length forming a heating coil 21 surrounding the 30 said core. The extremity of the coil is secured to the lowermost end of the screw member 19. The opposite end of the wire 20 projects slightly above the outer end of the core 18 and is provided with a binding screw 35 22 by means of which one terminal of an electrical circuit may be secured. The gasket or washer 23 of copper or any other suitable metal may be interposed between the screw member 19 and the outer shoulders of 40 the bushing 14.

The heating coil 21 within the nested elements 18 and 14' is of such arrangement or fineness as to require a low voltage and amperage to produce or generate a relatively 45 high degree of heat, and may derive its source of electrical energy from the source commonly used upon a vehicle for supplying current to the ignition or lighting systems thereof. This electrical source is indicated 50 generally at 24, wires 25 and 26 leading from the opposite poles thereof to be connected respectively to the binding screws 17 and 22 of the improved heating device. A switch 27 may be located within the circuit, 55 and preferably at a point within convenient reach of the motor operator, whereby the heating system may be switched on or off when desired.

In operation, when it is desired to main- 60 tain the water within the cooling system of the motor at a degree above the freezing point, the switch 27 may be closed, where- upon current will pass through the coil 21 from the source 24, within the shell 14' to 65 generate therein a relatively high degree of

heat. As the water adjacent the heater rises in temperature a current will be created throughout the cooling system, which system includes the cylinder jackets and the radiator. As the water slowly passes the 70 heating device, the heat will be radiated through the relatively thin walls of the porcelain shell 14' and a sufficient degree of heat will be maintained in the water to prevent the same from freezing. By reason of 75 the instalment of the device within the tubing connecting the radiator with the pump inlet, it is apparent that the device may be quickly and easily attached to or detached 80 from the cooling system.

While I have herein described and shown a particular or preferred embodiment of my invention, I wish it to be understood that I need not necessarily confine myself to all the precise details of construction herein set 85 forth by way of illustration, as modification and variation may be made without departing from the spirit of the invention or exceeding the scope of the claims.

I claim:

1. A heating device comprising in combination, a tubular member adapted for insertion in a fluid passage, supporting means integral with said tubular member, a bushing detachably secured in said supporting means, 95 a thin shell secured to said bushing to project into said tubular member, a closing member detachably inserted within the outer end of said bushing, an insulating core secured within said shell and spaced from the 100 walls thereof, a coil surrounding said core and having one end connected to said closing member and having its opposite end extending through said core, and means for connecting said coil in a circuit.

2. In a device of the class described, a tubular member adapted for insertion in the cooling system of a combustion engine, a nipple on said tubular member, a bushing detachably secured in said nipple, a porcelain shell secured to said bushing to project into said tubular member, a screw member inserted within the outer end of said bushing, a core secured to nest within said shell and to be spaced from the walls thereof, a 115 coil surrounding said core and having one end connected to said screw member, the opposite end of said coil projecting beyond said core, a binding screw in connection with said latter named end, a gasket between said nipple and bushing and a binding screw on said gasket, the said binding screws being adapted for connection with the wires of a source of electrical energy, substantially as described.

3. A heating device comprising in combination, a tubular member adapted for insertion in a fluid passage, supporting means integral with said tubular member, a bushing detachably secured in said supporting means,

a thin shell supported by said bushing to project into said tubular member, a closing member detachably inserted within the outer end of the bushing, an insulating core secured within said shell and spaced from the walls thereof, a coil surrounding said core and having one end connected to said closing member and having its opposite end extend-

ing through said core, and means for connecting said coil in a circuit.

In testimony whereof, I affix my signature, in the presence of two witnesses.

ALBERT R. CLARKE.
